UNITED STATES PATENT OFFICE

2,447,260

ELECTRON MICROSPECTROSCOPE

Ladislaus Marton, Menlo Heights, Calif., assignor
to Research Corporation, New York, N. Y., a
corporation of New York

Application June 21, 1945, Serial No. 600,761

10 Claims. (Cl. 250—49.5)

1

The invention relates to electron microspectroscopes.

It is known that when a beam of electrons is passed through a specimen of material under investigation the electrons are differentially decelerated and scattered in dependence on the varying density of the specimen thereby producing a pattern in the beam which may be enlarged and focussed by the suitable application of electric or magnetic fields to the beam to produce an image which may be made visible by allowing the beam to impinge on a layer of fluorescent substance or a photographic plate.

A purpose of the present invention is to provide apparatus for determining the composition of a specimen by subjecting an electron beam which has passed through a small selected area of the specimen to spectral velocity analysis.

Another purpose of the invention is to provide means for analyzing the velocity distribution of electrons which have passed through a small selected area of a specimen.

The velocity losses suffered by electrons passing through a specimen are characteristic of the atoms comprising the specimen and by analyzing the velocity distribution of the electrons after passing through the specimen the atomic constitution of the specimen may be determined.

The purposes of the invention may be accomplished by subjecting a selected narrow portion of a beam of electrons, which has passed through a specimen and has been highly magnified, to a deflecting field. After deflection the electrons of different velocities will follow divergent paths and will establish on an electron sensitive layer, such as a fluorescent or photographic layer, positioned in the focal plane of the deflected beam, a pattern corresponding to the velocity distribution of electrons in the beam and, therefore, to the atomic constitution of the portion of the specimen through which the deflected portion of the beam has passed.

The principles of the invention will be more fully described with reference to the accompanying drawings in which:

Fig. 1 is a diagrammatic representation of an electron microspectroscope embodying the principles of the invention;

Fig. 2 is an elevation in partial section of the electron velocity analyzer of the invention; and

Fig. 3 is a sectional elevation of the beam deflector on line 3—3 of Fig. 2.

In the diagrammatic representation of Fig. 1, A represents a conventional electron microscope, and B represents the electron velocity analyzer.

2

of the invention, a typical embodiment of which is shown in detail in Fig. 2. In Figs 1, 10 represents an electron source, such as the typical electron gun; 11 is a magnetic condenser which collects the electron beam from source 10; 12 is a specimen to be examined; 13 is a magnetic objective which produces an intermediate image at 14; and 15 is a magnetic image projector which produces at 16 a highly magnified image of a portion of the intermediate image. Any or all of the magnetic lens elements may be replaced by electrostatic lens elements, as is well known, provided that the high potential used for accelerating the electrons and for the operation of the lens elements is kept constant to the degree required for the elimination of the chromatic aberration. If this condition is not satisfied, an electrostatic deflecting system can be used by operating the analyzer with the same variable potential as the microscope elements.

In accordance with the invention, there is provided in the plane of the highly magnified image 16, a narrow slit 17 or other small aperture passing a beam 18 of electrons from a very small portion of the specimen which may be selected by varying the position of slit 17 in the magnified image. The electron beam 18 is subjected to a deflecting field 19, which may be magnetic or electrostatic or combined magnetic and electrostatic. The deflection of the electrons forming the beam is proportional to the strength of the field, which is substantially uniform and constant, and to the velocity of the electrons so that the electrons emerging from the deflecting field are grouped into divergent beams 18' and 18'' corresponding to the velocity species composing the beam 18. The distance of the deflecting field from the slit is preferably chosen so that the system focuses without the use of further lens elements. Since the focal distance for the electron components of different velocities will differ, the electron sensitive layer 20 is inclined at an angle which may be readily determined. The electron velocity spectrum produced by the analyzer can be observed by means of a fluorescent screen at position 20, and the spectrum can be recorded by photographing the fluorescent screen by means of a conventional photographic camera, or by placing a photographic emulsion layer in the focal plane 20 of the deflected electron beam, and observing the image.

By shifting the slit 17 with respect to the image, only electrons passing through a selected portion of the specimen will be analyzed. This can be effected either by shifting the specimen

stage of the electron microscope or by shifting the slit. The size of the analyzed area of the specimen can be varied by changing the magnification of the image at the position of the slit or by changing the width of the slit or by a combination of the two.

The typical embodiment of the electron velocity analyzer of the invention shown in Figs. 2 and 3 comprises a disk 22 provided with two holes 23 and 24. The disk fits into a circular recess 25 in the lower end of electron microscope 21 and is fastened thereto by means of a clamping ring 26 attached with bolts 27. A rubber gasket 28 is provided for sealing the two parts in a vacuum-tight manner. The top surface of the disk 22 is coated with fluorescent material and provided with an adjustable slit 29 in front of the circular hole 23. The slit blades are also coated with fluorescent material.

The divergent electron beam 30 producing an image on the fluorescent surface is adjusted so that the part of the image to be analyzed enters the slit 29. The electron beam entering the slit travels downward through tube 31 to enter a flat chamber 32 where it is deflected at 135° angle by means of a magnetic field perpendicular to the plane of the drawing. After deflection, it enters tube 33 which is attached by means of a flexible metallic bellows 34 to a small chamber 35. The metallic bellows is provided for orientation of chamber 35 by means of adjusting screws 34'. Chamber 35 is provided with a transparent fluorescent screen 36 on which the analyzed beam can be observed. Due to the fact that slit 19 provides too small a cross-section for producing the required high vacuum in the deflecting chamber, another tube 37 is provided which interconnects the different lower parts of the deflecting chamber and through which the same vacuum is maintained as in the electron microscope proper.

The magnetic field necessary for deflection of the beam is produced by means of an external electromagnet, shown in detail in Fig. 3. In Fig. 2, 38 indicates the location of the pole pieces shown in Fig. 3. These pole pieces 38 forming part of a conventional electromagnet consisting of a yoke 39 and coil 40 provide a relative homogeneous field. The whole electromagnet is mounted on a base 41 provided with three adjusting screws 42. These screws 42 permit the necessary alignment of the magnetic field for proper deflection.

It has been found advantageous to shield parts of the tubes 31 and 33 from the stray magnetic field produced by the electromagnet in order to localize its action to the deflecting chamber 32 alone. For this purpose, shields made of high permeability material 43 and 44 are placed around the tubes 31 and 33.

It has been found that relative motion of the magnetic field with respect to the remainder of the apparatus greatly impairs the resolution of the microspectroscope so that care should be taken to mount the electron microscope and the elements of the velocity analyzer in such a way as to eliminate the influence of external vibration.

The dispersion requirements and the resolving power of the analyzing system are largely determined by the velocity of the main beam and the velocity differences to be determined. In apparatus constructed in accordance with the invention, utilizing a main beam velocity of 70,000 electron-volts, velocity losses as low as 10 electron-volts can be determined.

With the arrangement shown in the drawing, the homogeneous deflecting field will concentrate all electrons of the same velocity at a definite distance varying with the velocity. The plane on which the images of the slit are properly focussed for electrons of different velocity is inclined at an angle of approximately 70° when the middle ray is deflected 135°, the middle ray being defined as the ray for which the distance of the image from the field is equal to the distance of the slit from the field.

Permanent magnets may be used instead of the electro-magnet shown by way of illustration or suitable electrostatic fields or combinations of magnetic and electrostatic fields may be used for deflecting the electron beam and focussing the divergent velocity components.

It will be seen that the apparatus of the invention makes possible the simultaneous observation of a highly magnified image of a specimen and of its characteristic electron velocity spectrum. A further advantage lies in the extremely small area of the specimen which can be selected for analysis, areas of the order of 1/100,000,000 of a square inch in magnitude having been observed with the apparatus of the invention.

Inasmuch as the apparatus of the invention may be readily utilized in the production of a record of the electron velocity spectrum, for example, by photographic recordation as was pointed out above, without altering in any manner the principles of operation of the apparatus, the term "microspectroscope" as used in the specification and claims is intended to include modifications of the apparatus for graphic recording or "microspectrographs".

I claim:

1. An electron microspectroscope comprising means providing a magnified electron image of a specimen, means defining a narrow aperture in the electron image plane, means providing an electron deflecting field in the path of the electron beam emerging from the aperture, and an electron-sensitive layer positioned in the focal plane of the deflected electron beam.

2. An electron microspectroscope comprising means providing a magnified electron image of a specimen, means defining a narrow aperture in the electron image plane, means providing an electron deflecting field in the path of the electron beam emerging from the aperture, and support means located adjacent the path of the deflected electron beam for positioning an electron-sensitive layer in the focal plane of the deflected electron beam.

3. An electron microspectroscope comprising means providing a magnified electron image of a specimen, means defining a narrow aperture in the electron image plane, means providing an electron deflecting magnetic field in the path of the electron beam emerging from the aperture, and an electron-sensitive layer positioned in the focal plane of the deflected electron beam.

4. An electron microspectroscope comprising means providing a magnified electron image of a specimen, means defining a narrow aperture in the electron image plane, means providing a substantially uniform constant rectilinear magnetic field normal to the path of the electron beam emerging from the aperture, and an electron-sensitive layer positioned in the focal plane of the deflected electron beam.

5. An electron microspectroscope comprising means providing a magnified electron image of a specimen, means defining a narrow aperture in

the electron image plane, means for varying the position of said aperture in the electron image plane, means providing an electron deflecting field in the path of the electron beam emerging from the aperture, and an electron-sensitive layer positioned in the focal plane of the deflected electron beam.

6. An electron velocity analyzer comprising means defining a narrow aperture in the plane of a magnified electron image, means providing an electron deflecting field in the path of the electron beam emerging from the aperture, and an electron-sensitive layer positioned in the focal plane of the deflected electron beam.

7. An electron velocity analyzer comprising means defining a narrow aperture in the plane of a magnified electron image, means providing an electron deflecting field in the path of the electron beam emerging from the aperture, and support means located adjacent the path of the deflected electron beam for positioning an electron-sensitive layer in the focal plane of the deflected electron beam.

8. An electron velocity analyzer comprising means defining a narrow aperture in the plane of a magnified electron image, means providing an electron deflecting magnetic field in the path of the electron beam emerging from the aperture, and an electron-sensitive layer positioned in the focal plane of the deflected electron beam.

20

25

30

9. An electron velocity analyzer comprising means defining a narrow aperture in the plane of a magnified electron image, means providing a substantially uniform constant rectilinear magnetic field normal to the path of the electron beam emerging from the aperture, and an electron-sensitive layer positioned in the focal plane of the deflected electron beam.

10. An electron velocity analyzer comprising means defining a narrow aperture in the plane of a magnified electron image, means for varying the position of said aperture in the electron image plane, means providing an electron deflecting field in the path of the electron beam emerging from the aperture, and an electron-sensitive layer positioned in the focal plane of the deflected electron beam.
